CARTON

Roy E. Lowey, Chicago, Ill., assignor to Container Corporation of America, Chicago, Ill., a corporation of Delaware

Application March 18, 1937, Serial No. 131,593

8 Claims. (Cl. 229—16)

The present invention relates to cartons and more particularly to folding cartons adapted to hold a plurality of separate articles such, for example, as fruits, vegetables, and other edible materials.

One object of the invention is to provide a container adapted to be set up by interlocking parts without the use of separate securing devices or special machinery.

Another object of the invention is to provide a container which may be packed through the bottom so that when the container is inverted the uppermost layer of articles packed in the container will present a pleasing and attractive appearance through a window formed in the top panel by the use of a sheet of transparent material inserted in a cutout in the top panel.

Another object of the invention is to provide a container of this type adapted to hold a definite count of edible articles in which such articles may be readily packed in graded sizes, the container being susceptible of being made up selectively into one of a plurality of sizes.

To these and other ends the invention resides in certain improvements and combinations of parts, all as will be hereinafter more fully described, the novel features being pointed out in the claims at the end of the specification.

In the drawings:

Fig. 1 is a perspective view of a container made in accordance with the present invention, illustrating same as it appears after it has been packed and placed in a position to effectively display the contents;

Fig. 2 is an enlarged fragmentary perspective view of the bottom or closure end of the container, being the end through which the container is normally filled;

Fig. 3 is a perspective view of the container in a partially set-up condition;

Fig. 4 is a view of the container blank;

Fig. 5 is a fragmentary perspective view of a modified form of container adapted to be selectively assembled to provide for varying capacities;

Fig. 6 is a perspective view, similar to Fig. 5, showing the container assembled to provide maximum capacity therein; and

Fig. 7 is a view of the blank of the modified form of container.

The container of the present invention is particularly advantageous for use in packaging of yieldable materials such as citrus fruits, apples, peaches, tomatoes, mushrooms, and similar fruits and vegetables. Due to the character of the

closure of the present container it is particularly well adapted for the packaging of mushrooms which, after being packed will generally increase in volume somewhat due to the fact that the mushrooms continue to grow for a short time.

Referring to Figs. 1 to 4, the carton, indicated as a whole at 10, comprises a top panel 11 and side panels 12, 13, 14 and 15 integral with the top panel and defined therefrom by score lines 16 as indicated. The top panel 11 preferably has an opening therein which is closed by a piece of transparent material 16 through which the contents of the carton may be viewed.

Means are provided for retaining walls 12 and 13 in an upright position and for closing the spaces between them so that the container may be packed without raising the walls 14 and 15. For this purpose the walls 12 and 13 are formed with extension flaps thereon indicated at 17 and 18 on wall 12, and at 19 and 20 on wall 13. Each of these flaps is provided with a suitable portion adapted to interlock with a similar portion on the cooperating flap. These interlocking portions are indicated at 17a, 18a, 19a and 20a. After these flaps have been engaged with each other the container will appear substantially as indicated in Fig. 3 and it is now ready to receive material. It is apparent that the interengaged pairs of flaps constitute in effect primary side walls which are supplemented and strengthened by side wall panels 14 and 15.

In order to form a bottom closure one of the side walls, in the present instance wall 14, is provided with an extension defined therefrom by a score line and divided by means of another score line into two sections one of which, indicated at 22, constitutes the bottom and the other section, indicated at 23, provides an upturned edge portion adapted to cause the bottom panel 22 to be disposed in a plane offset inwardly from the lower edges of the side walls of the carton.

Means are provided for retaining the bottom panel 22 in fixed position within the carton. For this purpose cut-out portions or notches 24, 25, 26 and 27 are preferably formed at the edges of the bottom panel 22 on its three free sides. The side wall 15 is provided with an extension 27 having a centrally disposed tongue 28 extending from its outer edge. An additional extension 29 is provided which is separated from the main extension 27 by means of a score line allowing it to be bent along a line even with the base of the tongue 28. When the bottom panel 22 is in place, as indicated in Fig. 2, the tongue 28

28 is arranged to ride on the surface of the bottom until it snaps into place between the edge of the bottom and the side wall in which position it will lie within the groove 25 formed in the bottom 22, and the extension 29 is arranged to contact against the lower surface of the bottom 22. It is to be noted that the tongue 28, when in place between the edge of the bottom and its adjacent side wall, will prevent dis-
10 placement of the extension 29 from its position in contact with the lower surface of the bottom.

The walls 12 and 13 preferably each have an extension thereon similar to that just described for the wall 15. The locking means on the wall 13 is indicated as comprising parts 30, 31 and 32 and the locking means on the wall 12 is indicated as comprising parts 33, 34 and 35, these parts being respectively equivalent to parts 27, 28 and 29 previously described. The parts 31 and 34, in the set-up condition of the carton, will be engaged in the cut-out portions 24 and 26 and the parts 32 and 35 will be engaged on the undersurface of the bottom 22. See Fig. 2. In assembling this form of the container it is not material which locking device is inserted first, thus the extension 29 may overlap one or both of the extensions 32 and 35, or extension 29 may be overlapped by one or both of said extensions.

30 When the carton has been assembled as just described the material contained in the carton will prevent movement of the bottom upwardly in the carton and the locking devices will prevent movement downwardly so that, so long as the 35 carton is filled with articles, there will be no likelihood of the bottom becoming accidentally displaced.

In the modified form of the invention, illustrated in Figs. 5, 6 and 7, the carton is preferably formed to permit its capacity to be varied. Thus if it is desired to pack articles by weight or count and the volume of such desired weight or count of articles should vary between different grades it will be possible to vary the volume of the carton so that the walls of the container will closely engage the contents and prevent same from shifting within the container thereby preventing injury to the contents.

As this form of the invention is also designed for upside down filling it is to be understood that reference to the top panel means the panel which is normally underneath during the packing operation; and reference to the bottom panel means the panel which is above at the close of packing 55 operation. When the packing operation is completed the container will then be inverted and retained in this position during further handling and shipment.

The modified carton is indicated as a whole by 60 the numeral 40 and comprises a top panel 41 to which walls 42, 43, 44 and 45 are hingedly connected. A transparent window 46 is provided for top panel 41. As illustrated in Fig. 7, the carton is preferably formed from a single blank of paper- 65 board, and, in the present instance, the walls are defined from the top panel by means of score lines, as indicated. In this embodiment of the invention the walls 42 and 43 will for convenience be termed side walls, and the walls 44 and 45 will be termed end walls. It is obvious, however, that the dimensions of the walls may be changed without altering the invention.

Means are provided for retaining the side walls 44 and 45 in one of a plurality of upright positions. For this purpose the side walls are pro-

vided at their ends with extension flaps 47, 48, 49 and 50. These extension flaps are each provided with notches 47a, 47b; 48a, 48b; 49a, 49b and 50a, 50b. The positions of the notches are such that when one set is engaged the effective lengths of 5 the interengaged flaps will be different from the effective length of same inter-engaged flaps when the other set of notches is engaged. Thus, for example, notches 48a and 50a constitute one set, and the sum of the distances of these notches 10 from the hinge connections of the flaps to the side walls is different from the sum of the distances of the notches 48b and 50b from the hinge connections of the flaps to their side walls. By this construction it is apparent that the lower 15 edges of the side walls (that is, the edges remote from the top panel) will be disposed closer or farther from each other dependent upon which set of notches is interengaged. When the flaps 48, 50 and 47, 49 are interengaged as just described the carton will be ready to receive the 20 contents which are to be enclosed therein.

In order to close the bottom of the carton a bottom panel 52 is formed as an extension on one of the side walls, being, in the present instance, 25 side wall 43. Between the bottom 52 and the side wall 43 is disposed a portion 53 which, upon being bent over against the wall 43, will cause the hinge line of the bottom to be disposed below the edge of the wall 43 as the carton is viewed in an 30 upside down position.

As in the form of the invention first described, one or more sets of locking means are provided on the edges of the remaining walls to retain the edges of the bottom panel in a fixed position 35 offset inwardly from the lower free edges of the walls. For this purpose the wall 42 is provided with an extension 54 defined from the wall 42 by a score line and carrying tongues 55 and 56 thereon adapted to lie between the edge of the 40 bottom panel and the inner face of side wall 42. An additional extension 54a is provided on the portion 54 and is defined therefrom by a score line impressed in line with the bases of the tongues 55 and 56 permitting the portion 54a to lie flat on 45 the outer face of the bottom panel.

End walls 44 and 45 are provided with similar bottom locking portions which comprise extension 57, tongue 58 and extension 59 on wall 44; and extension 60, tongue 61 and extension 62 on 50 wall 45.

In order to facilitate the introduction of the tongues 55, 56, 58 and 61 between the edges of the bottom panel and the adjacent side walls there is preferably formed in the bottom panel a plurality 55 of cut out portions or notches indicated respectively at 63, 64, 65 and 66. These notches are equivalent to notches 24, 25 and 26 of the form first described.

Means are provided by which the bottom panel 60 52 can be formed narrower. For this purpose a score line 66a is impressed in the panel 52 back a short distance from the free edge of the bottom to define a portion 67 which may be bent over to lie against the side wall 42 in the set-up condition 65 of the box. The use of the portion 67 may best be understood by comparison of Figs. 5 and 6. In Fig. 6 the portion 67 is disposed in the plane of the bottom panel 52, while in Fig. 5 the portion 67 is removed from the plane of the bottom and 70 lies against the side wall 42 thus narrowing the panel 52 by the width of the portion 67.

In order to provide means by which tongues 55 and 56 may be engaged with the bottom panel when formed in its narrow condition there are 75

provided slits 68 and 69 preferably shaped in a similar manner to the cuts 64 and 65 and having their ends terminating along the hinge line between the panel 52 and the portion 67. Thus when the portion 67 is bent substantially at right angles to the panel 52 openings will be provided into which the tongues 55 and 56 may enter. If desired, the portion 67 may be completely severed from the bottom panel along line 66 when it is desired to form a carton with the narrower width bottom.

In using the cartons illustrated in the Figs. 5, 6 and 7 the volume of the goods to be packed in the carton is determined, whereupon the side walls 42 and 43 will be bent upwardly and the flaps 48, 50 and 47, 49 are engaged by interconnecting the notches 48a and 50a and notches 47a and 49a, if the large size is required; or, if the smaller size is required, the notches 48b and 50b, and 47b and 49b will be engaged.

If the container is made up for the larger volume the bottom panel 52 will be left as indicated in Fig. 6, but if the carton is to be made up for the smaller volume the portion 67 will be removed or folded to lie against the side wall 42 as indicated in Fig. 5. In either event the locking devices on the remaining walls will be folded inwardly to engage the tongues 55, 56, 58 and 61 in between such walls and the edges of the bottom panel. The members or portions 54a, 59 and 62 will be folded to lie on the outer surface of the bottom panel as partially indicated in Figs. 5 and 6, and in a manner similar to that indicated in Fig. 2. It is to be noted that the presence of extended portion 54a beneath the bottom 52, when used in its larger size, will tend to prevent bending of the bottom along score line 66 when the bottom is supporting the contents of the carton.

40 In preparing the blanks for any given type of commodity it is desirable to dimension the effective interior height of the carton so as to snugly retain the material to be packed therein. By so doing, the bottom panel, after the container is filled, will come to rest on the contents at approximately the proper level so that when the portions 54, 57 and 60 are folded inwardly against their attached walls of the tongues 55, 56, 58 and 61 will snap into place within the respective opening 64, 65, 66 and 63 with the portions 54a, 59 and 62 lying on the outer surface of the bottom panel 62.

Due to the use of the interconnected flaps 17, 19 and 18, 20, together with panels 14 and 15, it is apparent that a very sturdy construction of container is provided so that, if desired, the filled containers may be stacked in piles of considerable height without likelihood of collapsing the container walls. The provision of the bottom locking means on the ends of certain side walls which locking means include a portion engaging the bottom (these portions being indicated at 29, 32 and 35, in Fig. 4) cause the bottom panel to be reinforced and strengthened to such an extent that it is possible to use lighter stock in making up the cartons than it otherwise would be if these extended flaps were not employed.

While the present description sets forth a preferred embodiment of the invention, numerous changes may be made in the construction without departing from the spirit of the invention, and it is therefore desired that the present embodiment be considered in all respects as illustrative and not restrictive, reference being had to the

appended claims rather than to the foregoing description to indicate the scope of the invention.

I claim:

1. A carton adapted to be assembled selectively so as to have one of a plurality of different capacities and adapted to be filled in an upside-down position, said carton comprising a rectangular top panel, side walls integrally hinged on opposite sides thereof, extension flaps on the edges of said side walls, said extension flaps having two sets of cooperating engaging portions of which one set only is adapted to cooperate at a given time, said sets of cooperating portions being so related to the flaps that one set will cause the lower edges of the side walls to be located closer together than will result when the other set of cooperating portions are engaged with each other, a bottom panel adapted to close the bottom of the box, and means for securing the bottom panel in place. 20

2. A carton adapted to be assembled selectively so as to have one of a plurality of different capacities and adapted to be filled in an upside-down position, said carton comprising a rectangular top panel, side walls integrally hinged on each side thereof, extension flaps on the edges of two oppositely disposed of said side walls, said extension flaps having two sets of cooperating engaging portions of which one set only is adapted to cooperate at a given time, said sets of cooperating portions being so related to the flaps that one set will cause the lower edges of the side walls to be located closer together than will result when the other set of cooperating portions are engaged with each other, a bottom panel 35 adapted to close the bottom of the box, and means for securing the remaining side walls and the bottom panel in place.

3. A carton adapted to be assembled selectively so as to have one of a plurality of different capacities and adapted to be filled in an upside-down position, said carton comprising a rectangular top panel, side walls integrally hinged on each side thereof, extension flaps on the edges of two oppositely disposed of said side walls, said extension flaps having two sets of cooperating engaging portions of which one set only is adapted to cooperate at a given time, said sets of cooperating portions being so related to the flaps that one set will cause the lower edges of the side walls to be located closer together than will result when the other set of cooperating portions are engaged with each other, a bottom panel 50 means on the bottom panel for decreasing the effective area thereof to enable it to cooperate with the walls when same are located in positions adapted to decrease the volume of the carton, said means comprising a readily foldable edge portion which, upon being removed from the plane of the bottom panel will permit the bottom panel to be fitted with respect to the walls in their reduced capacity position, means on the side walls opposite the side wall supporting the bottom for retaining the free edge of the bottom in place, and means for securing the remaining 55 side walls in place.

4. A carton adapted to be assembled selectively so as to have any of a plurality of different capacities comprising, a generally rectangular top panel, side walls integrally hinged on opposite 70 sides thereof, one pair of oppositely disposed side walls bearing interlocking flaps adapted to be interengaged to hold said side walls in upright positions, one of the remaining pair of oppositely disposed side walls at its outer edge having an 75

extension hinged thereto by one edge and adapted to form a bottom, means on said extension for decreasing the effective area thereof, and means for decreasing the volume encompassed by the side walls in accordance with the decrease in effective area of the extension.

5. A carton adapted to be assembled selectively so as to have any of a plurality of different capacities comprising, a generally rectangular top panel, side wall panels integrally hinged along each edge of said top panel, interlocking means carried by certain of said side wall panels for securing said walls in any of a plurality of predetermined angular relationships with respect to 10 said top panels, a bottom panel carried by one of said side panels, and means for varying the effective area of said bottom panel to accord with the predetermined angular positions of said side wall panels.

15. 6. A carton for retaining yieldable materials and adapted to be filled in an upside-down position, said carton comprising a rectangular top wall, four side walls associated therewith, means for engaging the side walls in container-forming 20 position, a bottom panel hingedly associated with one of the side walls along a line spaced inwardly from the lower edge of said side wall, and means for retaining and supporting the bottom panel in position above the lower edges of 25 the side walls when the carton has been placed in upright position, said means comprising a down turned flap extension on at least one of the remaining side walls, a tongue part extended from its outer edge and inserted between the 30 side wall and the adjacent edge of the bottom panel and an additional extension separated from the main extension by means of a score line and extending beyond and on each side of the tongue, said additional extension being folded 35 to lie flat against the lower face of the bottom panel, whereby, when the carton has been filled with yieldable contents, the bottom wall may be engaged in place between the contents and the flap extension by moving the flap extension across the surface of the bottom wall until the tongue part snaps into place between the bottom and the side wall.

40. 7. A carton for retaining yieldable materials and adapted to be filled in an upside-down position, said carton comprising a rectangular top wall, four side walls associated therewith, means for engaging the side walls in container-forming 45 position, a bottom panel hingedly associated with

one of the side walls along a line spaced inwardly from the lower edge of said side wall and being provided with a shallow notch in an edge thereof, and means for retaining and supporting the bottom panel in position above the lower edges 5 of the side walls when the carton has been placed in upright position, said means comprising a flap extension on at least one of the remaining side walls, said flap extension comprising a tongue part inserted into the space provided between the 10 notched edge of the bottom wall and the adjacent side wall, said flap extension also including another part extending beyond the tongue and folded to lie flat against the lower face of the bottom panel, whereby, when the carton has been filled with yieldable contents, the bottom wall may be engaged in place between the contents and the flap extension by moving the flap extension across the surface of the bottom wall until the tongue part snaps 15 into the space provided by the above mentioned notch in the edge of the bottom wall.

8. A carton for retaining yieldable materials and adapted to be filled in an upside-down position, said carton comprising a rectangular top wall, four side walls associated therewith, means for engaging the side wall panels in container-forming position, a bottom panel hingedly associated with one of the side walls along a line spaced inwardly from the lower edge of said side wall and being provided with a shallow notch in an edge thereof, and means for retaining and supporting the bottom panel in position above the lower edges of the side walls when the carton has been placed in upright position, said means comprising a flap extension on at least one of the remaining side walls, said flap extension comprising a centrally disposed, rigid tongue part inserted into the space provided between the notched edge of the bottom wall and the adjacent side wall, said flap extension also including another part, extending beyond and on each side of the tongue part, and folded to lie flat against the lower face of the bottom panel, whereby, when the carton has been filled with yieldable contents, the bottom wall may be engaged in place between the contents and the flap extension by moving the flap extension across the surface of the bottom wall until the tongue part snaps into the space provided by the above mentioned notch in the edge of the bottom wall.

30. 35. 40. 45. 50. ROY E. LOWEY.
